CIRCULAR WATER CRAFT

Jeffrey J. Taylor, 1689 Kilmer Road,
Vancouver, British Columbia, Canada

Filed Oct. 23, 1968, Ser. No. 14,147

Term of patent 14 years

Int. Cl. D12—06

U.S. Cl. D71—1

FIG. 1 is a perspective view of a circular water craft showing my new design,

FIG. 2 is a side view thereof,

FIG. 3 is a plan view thereof,

FIG. 4 is a bottom view thereof,

FIG. 5 is a view, partly in vertical section and partly in elevation, on a reduced scale.

I claim:

The ornamental design for a circular water craft, as shown.
